UNITED STATES PATENT OFFICE.

WALLACE R. DOUGLAS, OF CRETE, NEBRASKA.

FOLDING TABLE.

Application filed October 2, 1924. Serial No. 741,175.

To all whom it may concern:

Be it known that I, WALLACE R. DOUGLAS, a citizen of the United States, residing at Crete, in the county of Saline and State of Nebraska, have invented certain new and useful Improvements in Folding Tables, of which the following is a specification.

My invention has for its object the provision of a folding table. Since my table was designed initially and primarily to meet the demand for a camp table for use on automobile and similar trips, I will describe it with particular reference to that use.

Such a table should be light in weight and it should be foldable into a compact bundle. It must have no loose parts and its folding and unfolding features should be of the utmost simplicity. Since the table is of necessity subjected to considerable rough usage it must be staunch and rugged, and it must be sanitary even under the unfavorable conditions of an extended tourist camping trip. In brief, it is the primary object of my invention to provide a folding table having these features. Other objects will be pointed out in the following description.

Referring now to the drawings,

Figure 1 is a view and perspective of my table as it appears when set up.

Figure 2 is a perspective view of the underside of my table at one of its corners.

Figure 3 is a sectional view of the folded table, a portion being broken away.

Figures 4 and 5 are interior views of a portion of the table showing particularly the latch for holding the leaves of the table in set up position.

The table top is made up of two leaves 10 and 11, leaf 10 being the larger of the two and of a size to snugly enclose the leaf 11. Both leaves are formed with double flanges on all of its edges as shown in Figure 3, the flanges being double in order to expose round or folded edges rather than rough cut edges. In the set up table these flanges are all downturned. The flanges 12 at the meeting edges of the leaves are narrower than the outer flanges. The side flanges all project inwardly and are rounded, thus forming rounded ears 13 for receiving the pivot pins 14 which pivotally connect the two leaves.

The flanges 12 have substantially half the width of the outer flanges and the pivot pins 14 are in alignment with the free edges

of the flanges 12. In the set up position of the table the flanges 12 limit the pivotal movement of the leaves and serve to hold the table top rigid. The table may be heavily loaded without depressing the top at its middle portion. When the table is folded the flanges 12 of the two leaves will meet along their free edges to completely close that edge of the folded table. The leaf 11 folds into the leaf 10 forming a closed box like structure when the table is folded.

In order to prevent the accidental upward displacement of the leaves 10 and 11 when the table is set up, the latch shown in Figures 4 and 5 may be employed in conjunction with either or both pivots 14. The latch consists of a leaf spring 15 which is spot welded, preferably at two points, to the inner surface of the flange. The spring 15 is provided with a pin 16 for entering a suitable aperture in the overlying flanges of the leaves and with an ear 17 for facilitating the release of the pin 16 from the aperture when it is desired to fold the table.

The table is supported at its four corners by the legs 18 and 19 which are pivotally connected to the table top on its under side in such a manner that each pair of legs is foldable into alignment inside the table top. The legs are all made of channeled steel and are of equal length, the relative cross sectional dimensions being such that each leg 19 is foldable into the companion leg 18.

The relationship of the legs to the table top and the bracing system of the legs is best shown in Figure 2, which shows the underside of the table with the leg in partly folded position. The rectangular plate 20 is welded to the under side of the table top in the corner. The plate 20 has two depending ears 21 which are apertured for pivotal connection with the leg. A plate 22 is secured, preferably by welding, to the back wall of the channeled leg at its upper extremity, and this plate has its tapered extremity inturned to form an ear 23 which is pivotally secured to the inner of the pair of ears 21. A second pivotal connection is formed between the leg directly and the other ear 21 of the pair, the two pivots being in alignment. The plate 22 is long enough to prevent lateral play of the leg and thus acts as a transverse brace for the leg. In the set up position of the table, the end

flanges limit the pivotal movement of the legs and prevent their spreading.

To prevent the collapsing of the table when in use I provide braces with toggle latches for all of the legs. The upper link 24 of each brace is pivotally secured to a support 25 which is welded to the under side of the table top. The lower link 26 of the brace is pivoted to its leg and it is provided with a toggle abutment for holding the links in alignment. There is a difference, however, between the linkages for the legs 18 and 19. In the case of the legs 18 the links lie between the lateral flange of the table top and contiguous wall of the leg 18, the links 24 and 26 being entirely outside the leg. In the leg 19, however, the links are entirely within the leg when the table is folded.

As before stated, my table is designed primarily for use on camping and tourist trips. When set up it is a rugged table of ample size and when folded it forms a compact bundle occupying very little space and having no projections. The legs occupy only a very small part of the space within the folded table, leaving ample room for the table linen and silverware, which are thus fully protected from dust. The folding and unfolding of the table requires only a few seconds' time, which is a vital factor in any table designed for tourist use. When set up, the space underneath the table is open and free, there being no braces which would prevent the users from sitting close to the table and getting their legs underneath. The table being all metal and enameled is easily kept in sanitary condition.

The table has however, other uses than those mentioned. It is admirably adapted for use as a card table. Since it occupies very little room when folded, it may be used as a supplemental table in the bed room, screened porch, or in the office. Because it can be so easily stored away when not in use it is particularly useful as a clerk's table in voting places, it being my intention to manufacture the table in a size convenient for this purpose, to be used either with or without the collapsible voting booths.

Having thus described my invention in terms which will be readily understood by others skilled in the art to which it pertains, what I believe to be new and desire to secure by Letters Patent of the United States is:—

A table leg and means for securing said leg to the table top on the under side thereof, said means including a plate which is adapted to be secured to the table top at the under side thereof, spaced ears on said plate, a triangular brace rigidly secured to said leg adjacent its upper extremity, said triangular brace and leg being pivotally connected with the ears of the said plate, said leg being thus foldable into parallelism with the table top, a support which is adapted to be secured to the table top in the path of the leg, and a foldable brace pivotally connected with said leg and with said support, said foldable brace being adapted to hold said leg in perpendicular relation to the table top.

In testimony whereof I affix my signature.
WALLACE R. DOUGLAS.
